UNITED STATES PATENT OFFICE

JESSE O. MATTESON, OF MUSKEGON, MICHIGAN, ASSIGNOR TO THE BRUNSWICK-BALKE-COLLENDER COMPANY, OF CHICAGO, ILLINOIS, A CORPORATION OF DELAWARE

DESIGN FOR A BILLIARD TABLE

Application filed August 6, 1932. Serial No. 44,537. Term of patent 3½ years.

To all whom it may concern:

Be it known that I, JESSE O. MATTESON, a citizen of the United States, residing at Muskegon, in the county of Muskegon and State of Michigan, have invented a new, original, and ornamental Design for Billiard Tables, of which the following is a specification, reference being had to the accompanying drawing, forming part thereof.

In the drawing—

I claim:

The ornamental design for a billiard table as shown.

JESSE O. MATTESON.
